H. FOTHERGILL

BOILER FEED WATER SUPPLY PLANT

Filed March 5, 1924

INVENTOR:

HARRY FOTHERGILL

By Spear, Middleton, Donedon & Hare
Atty.

Patented July 13, 1926.

UNITED STATES PATENT OFFICE.

HARRY FOTHERGILL, OF WESTMINSTER, LONDON, ENGLAND.

BOILER-FEED-WATER-SUPPLY PLANT.

Application filed March 5, 1924, Serial No. 697,104, and in Great Britain March 9, 1923.

This invention relates to improvements in or relating to steam turbine plant in which means are provided for removing the air from the boiler feed water by heat treatment in a vessel generally called a deaerating apparatus. In steam power plants, it frequently happens, especially where auxiliaries are electrically driven, that there is not sufficient low pressure steam available for heating the feed water to the desired temperature, and steam is bled from a steam turbine and used in a separate feed water heater for this purpose.

The object of the present invention is to utilize steam bled from the turbine for effecting at one and the same time the dual operation of heating and deaerating the feed water.

When it is desired to maintain a low pressure in the chamber in which the water is deaerated by placing it in connection with a main condenser under vacuum, I prefer to arrange in such connection a nozzle or equivalent device for the purpose of limiting to a predetermined amount the quantity of aerated vapour passing from the deaerator to the condenser by the choking effect of the nozzle.

By this means the pressure in the chamber in which the water is deaerated is automatically adjusted to that pressure corresponding to the boiling point of the water, notwithstanding variations in the quantity of water treated in the deaerator or in the steam available for heating, because by the use of a free opening such as a nozzle the pressure in the deaerator adjusts itself to maintain the production of the water vapor necessary to fill the nozzle opening.

The deaerating apparatus may be of the type in which the water is raised in temperature by direct contact with the steam, but I prefer the arrangement in which the water is heated by surface contact.

The accompanying drawing illustrates an embodiment of my invention wherein a deaerator is employed in which the heat treatment is effected by surface contact. In the arrangement illustrated *a* is the main turbine, *b* the deaerator and *c* the main condenser from which the air is removed by the ejector *d*. The pump *e* removes the condensate from the condenser *c* and discharges through the pipe *f* into the deaerator *b* from which the deaerated water is removed from pipe *g* by the pump *h*. Low pressure

steam is bled from the turbine through the pipe *l* under control of the valve *m* and is used in the tubes *t* for raising the water to the desired temperature. *n* is a drain connection through which the condensed steam from the tubes is discharged into the condenser *c*. The deaerator *b* is maintained under vacuum by placing it in communication with the condenser *c* by way of the pipe *p*. This pipe *p* is provided with a nozzle or equivalent device *o* for the purpose of limiting to a predetermined amount the quantity of aerated vapour passing from the deaerator *b* to the condenser *c* by the choking effect of the device *o*. Any restricted opening in the pipe *p* will give this desired effect, and in the arrangement shown, an ordinary valve, opened to the desired extent, is illustrated. By the use of this restricted opening the pressure in the deaerator is maintained at that corresponding to the temperature of the water therein, while a predetermined amount of aerated vapour is continuously discharged through the pipe *p*.

By using bled steam from a low pressure section of the turbine it follows that the quantity of such bled steam will vary in accordance with the load on the turbine; therefore this method of working has the great advantage that the steam supply is automatically adjusted and no special device for this purpose need be provided. For example, when the turbine is under light load, the pressure in the low pressure section of the turbine will be reduced and less steam will pass to the deaerator. Alternatively, if the turbine is under full load, the pressure in the low pressure section is increased and more steam will pass to the deaerator.

Under such conditions the tendency will be automatically to deliver steam to the deaerator in correspondence with the water passing therethrough.

What I claim and desire to secure by Letters Patent is:

1. Steam power plant comprising a steam turbine, a condenser to which said turbine exhausts, a deaerating apparatus, a connection between the deaerating apparatus and the condenser for maintaining the deaerating apparatus under vacuum, a choking device in said connection for limiting the quantity of aerated vapour passing from the deaerating apparatus to the condenser, means

for delivering condensate from the condenser to the deaerating apparatus, a connection between the turbine and the deaerating apparatus for conveying steam from said turbine to said deaerating apparatus, and means for conveying the heated and deaerated water from the deaerating apparatus to the boiler feed system.

2. Steam power plant comprising a steam turbine, a condenser to which said turbine exhausts, a deaerating apparatus, a connection between the deaerating apparatus and the condenser for maintaining the deaerating apparatus under vacuum, a valve in said connection for limiting to a predetermined amount the quantity of aerated vapour passing from the deaerating apparatus to the condenser, means for delivering condensate from the condenser to the deaerating apparatus, a connection between the turbine and the deaerating apparatus for conveying steam from said turbine to said deaerating apparatus, and means for conveying the heated and deaerated water from the deaerating apparatus to the boiler feed system.

3. Steam power plant comprising a steam turbine, a condenser to which said turbine exhausts, deaerating apparatus provided with heating tubes, means for delivering condensate from the condenser to the deaerating apparatus, so as to fall on said tubes, a connection between the turbine and the de-

aerating apparatus for conveying steam from said turbine to and through the tubes of said deaerating apparatus, a drain connection from the deaerating apparatus to the condenser through which the condensed steam from the tubes of the deaerating apparatus is delivered to the condenser, and means for conveying heated and deaerated water from the deaerating apparatus to the boiler feed system. 35 40

4. Steam power plant comprising a steam turbine, a condenser to which said turbine exhausts, a deaerating apparatus, having steam heated surface, a connection between the deaerating apparatus and the condenser for maintaining the deaerating apparatus under vacuum, means for delivering condensate from the condenser to the deaerating apparatus, so as to fall on the steam heated surface, a connection between the turbine and the deaerating apparatus for conveying steam from said turbine to heat the surface within said deaerating apparatus, means for draining the condensed steam from the heating surface of the deaerating apparatus to the condenser, and means for conveying the heated and deaerated water from the deaerating apparatus to the boiler feed system. 45 50 55 60

In testimony whereof I affix my signature.

HARRY FOTHERGILL.
